SPLICING THREAD FEED MECHANISM FOR KNITTING MACHINES.

No. 440,606.

Patented Nov. 11, 1890.

UNITED STATES PATENT OFFICE.

WILLIAM H. PEPPER AND ALBERT T. L. DAVIS, OF LAKE VILLAGE, ASSIGNORS
TO THE PITMAN MANUFACTURING COMPANY, OF LACONIA, NEW HAMPSHIRE.

SPLICING-THREAD-FEED MECHANISM FOR KNITTING-MACHINES.

SPECIFICATION forming part of Letters Patent No. 440,606, dated November 11, 1890.

Application filed March 17, 1890. Serial No. 344,085. (No model.)

To all whom it may concern:

Be it known that we, WILLIAM H. PEPPER and ALBERT T. L. DAVIS, of Lake Village, in the county of Belknap and State of New Hampshire, have invented certain new and useful 5 Improvements in Splicing-Thread-Feed Mechanism for Knitting-Machines, of which the following is a specification.

The present invention is for the same purpose as that described and set forth in our 10 application for Letters Patent of the United States, filed February 5, 1890, Serial No. 339,297. In said application there is described a circular latch-needle knitting-machine for 15 forming knitted ribbed tubular webs in which a re-enforcing patch is automatically knitted into the web, said patch being formed by running in a splicing-thread and breaking it off at each round of stitches. In the mechanism 20 set forth in said application the splicing-thread is fed in by the frictional contact therewith of the main thread, and the application was based more particularly upon mechanism for slackening the splicing-thread, in order 25 that the same may be loose and entirely free from tension at the moment when it is fed in (at each round of stitches) by the frictional contact of the main thread, the purpose being to enable the splicing-thread to be fed in with 30 certainty and uniformity at each round.

Now, the present invention consists in a different and improved mechanism for slackening the splicing-thread for the same object and purpose and in the gripping mechanism 35 co-operating with said slackening mechanism.

In the accompanying drawings we have illustrated the present improved thread-slackener applied to a well-known type of circular latch-needle knitting-machine for knitting 40 ribbed webs, such as is also shown in said above-named application.

In the drawings, Figure 1 is a side view of the head of the knitting-machine provided with the present improved thread-slackener. 45 Fig. 2 is a plan view thereof, and Figs. 3, 4, 5, 6, 7, 8, and 9 are views of parts in detail.

Like reference figures and numbers designate corresponding parts in all of the figures, and reference-letters are used to designate

parts common with similar parts in said application, while reference-numerals are employed to designate new parts or those differing from corresponding parts in said application.

A is the usual head-plate of a circular-knitting machine.

B is the constantly-rotating cylinder or ring which operates the cylinder-needles.

C is the stationary needle-cylinder.

D is the stationary dial-needle plate, and 60 E is the constantly-rotating dial-cam plate which actuates the dial-needles and which is rigidly connected with the cylinder or ring B by means of a spindle *a* and bracket-arm *b*. The thread-guide plate F is secured by a 65 bracket-arm G to the cam-plate E, so as to rotate therewith, and is provided with a single leading-in thread-guide eye *c*, through which both the main thread *x* and the splicing-thread *y* pass.

The splicing-thread bobbin H is carried by a bracket I, centrally supported on the rotating spindle *a*, so that the bobbin turns with the thread-guide. To the bracket I is secured a vertical post *d*, having a horizontally-extending tension-bar *e*, suitably bent or notched at *f* to constitute a thread-guide, which in turn may, if desired, carry an outwardly-projecting spring-arm *g*, having on its outer extremity a tension-thread eye *h*. The 80 splicing-thread passes upwardly from its bobbin H, over the bar *e* in the guide-notch *f*, and thence downwardly toward the thread-eye *c* in the guide-plate F.

In accordance with the present improvement the course of the splicing-thread from eye *h* to eye *c* is different from its course in said application. In the present case the bracket-arm G is provided at its outer end, above the guide-plate F, with a vertical radially-extending plate 10. Considering that side of the plate 10 to be the front side, which is in advance as it rotates, it carries on its front side and at its upper part two splicing-thread guides 11 and 12. The first of these 90 guides 11 is an open loop mounted directly above the vertical plate 10, and the other guide 12 is conveniently formed by a wire 13,

extending outwardly from the plate 10 and in front of the same. This wire is bent inwardly in a horizontal plane, and is bent or recessed to constitute the guide 12. The guide 12 is in approximately the same horizontal plane as the guide-loop 11. The bracket-arm G also carries a plate 14, extending outwardly beyond the guide-plate F, and in it is formed a thread-eye 15, which is located in the near neighborhood of the leading-in thread-eye c. The splicing-thread y is carried from tension-eye h under the loop-guide 11, thence over the guide 12, thence through the eye 15, and finally through the leading-in eye c. The splicing-thread between guides 11 and 12 extends in a substantially horizontal plane, and the three guides 11, 12, and 15 are in substantially the same vertical plane. The eye 15 is just outside of the outer face of the guide-plate F, so that between the eyes 15 and c the splicing-thread extends close along the outer surface of the guide-plate F.

The main thread x is led from its bobbin (which may be located at any convenient place) through tension and guide-eyes i i on the post d. From the last of these eyes i it extends to and through a guide-eye 16 in the plate 14, and thence through the leading-in eye c. The guide-eye 16 is located in front of the eye c and nearly in a radial line therewith, and in substantially the same horizontal plane, for reasons which will hereinafter appear.

In describing the mechanisms and operations involved in feeding in the splicing-thread and in breaking it off at each round of stitches the latter will be first set forth, since an understanding of the breaking-off mechanism is prerequisite to a clear comprehension of the feeding-in mechanism, of which the splicing-thread slackener forms a part.

The splicing-thread is broken off automatically at each round by a gripper, which grips the splicing-thread and holds it from being fed in, so that the splicing-thread is broken by the continuance of the knitting operation, and the splicing-thread cannot be again fed in until it is released by the gripper. The gripper is composed of a fixed gripping-jaw and a movable gripping-jaw. The outer face of the guide-plate F itself constitutes in the present instance the fixed gripping-jaw. The movable gripping-jaw comprises an elbow-lever having a horizontal arm 17 and a vertical arm 18. The inner end of the horizontal arm is pivoted at 19 to the upper inner part of the front face of the vertical plate 10. The vertical arm 18 by its own weight rests against the outer face of the guide-plate F, its inner gripping-surface lying flush with the outer face of said plate F. The position of the movable gripper-jaw is such that its vertical arm 18 extends between the splicing-thread eye 15 and the leading-in eye c, so that it grips that portion of the splicing-thread which extends between said eyes. The movable gripping-

jaw is moved to and from the fixed jaw (or plate F) by swinging it on its pivot 19. When it is swung out from the plate, the splicing-thread is free to be fed in by the frictional contact therewith of the main thread, and when the movable gripping-jaw is swung in against the plate F it grips the splicing-thread, (whereby the latter is broken off,) and the feeding in of the splicing-thread is discontinued as long as the movable gripping-jaw is against the plate F. The gripping of the splicing-thread, therefore, by the gripper determines the point in each round where the splicing-thread is broken and where the patch terminates, and the release of the splicing-thread by the gripper is prerequisite to enable the splicing-thread to be fed to the needles. During the knitting of the unspliced portions of the web the gripper always holds the splicing-thread, so that in the normal position of the gripper the splicing-thread is inactive. The gripper is primarily brought into operation by means of a pattern-chain K, operated in a usual manner and having at proper intervals cams m (which initiate the splicing operation) and cams n, (which discontinue the splicing operation.) The cams m and n occupy different planes on the pattern-chain. The number and relative positions of the cams m n on the pattern-chain are determined by the character of the work to be done, and as such a pattern-chain is in itself old and well known only one cam m and one cam n are shown. The pattern-cams m n co-operate, respectively, with two vertically-movable rods L M, guided in suitable ways formed in a bracket N, fixed to the head-plate A. The pattern-cams lift the rods, and when the cams have passed the rods drop by gravity, their downward movement being limited by guide-pins o o, working in suitable guide-slots, said guide-pins also preventing any rotation of the rods in their respective ways.

Pivoted at p to the upper face of the bracket N is a horizontally-swinging lever P, coacting with both rods L and M, its pivotal point being located between the said rods, so that when the inner rod M is raised it will swing the lever in the direction indicated by the arrow 2, and when the outer rod L is raised it will be swung in the opposite direction. The coacting faces of the rods L and M and of the lever P are properly beveled (see Fig. 3) to render their movements easy. Whenever moved to either position by one of the rods, the lever remains there until acted upon by the other rod.

Alongside the lever P and pivoted to the outer end of the bracket N on its side is a vertically-swinging lever Q, the free end of which is held from lateral displacement (and the downward movement thereof limited) by proper guides on or in the bracket N. This lever Q is acted upon by the lever P in such manner that it is lifted by said lever P when the latter is moved by the outer rod L. This is conveniently accomplished by a beveled or

cam-shaped projecting tongue *q* on the inner end of the horizontally-swinging lever *P*, which registers with an aperture *r* in the vertically-swinging lever *Q*. When the lever *P* is operated by the outer rod *L* its tongue enters the aperture *r*, and the cam-face of the tongue, engaging the upper margin of said aperture, raises the free end of the lever *Q*. The lever *Q* remains in this elevated position until the lever *P* is acted upon by the inner rod *M*, which swings lever *P* so as to disengage its cam-tongue from the aperture in lever *Q*, which latter then resumes by gravity its normal lower position.

The lever *Q* carries on its inner end a gripper-actuating cam-plate *R*, the essential characteristic of which is that its outer cam-face is at an incline to a radial line drawn from the axis of the machine, and the forward edge of this outer cam-face—that is, its edge which is first encountered by the tappet-pin *T*, hereinafter referred to—is nearer the axis of the machine than its rear edge, as shown in Fig. 2. When the lever *Q* is raised, this gripper-actuating cam-plate is brought into the path of a rotating part which is in operative connection with the movable splicing-thread-gripping jaw 17 and 18, and the cam-plate remains in this operative position until the lever *Q* resumes its normal position after the completion of the spliced section or patch. The essential operation, therefore, of the mechanism between the pattern-chain and the gripper-actuating cam-plate (which is identical with that set forth in the above-named application) is such that the said cam-plate is brought into operative position when the formation of the patch is to be initiated, remains in this operative position during the entire formation of the patch, and resumes its normal inactive position on the completion of the patch.

The movable gripping-jaw 17 18 is acted upon directly by a horizontal radial reciprocating cam-bar *S*, which slides in a radial horizontal line in suitable ways formed in or on the bracket-arm *G* and its vertical plate 10. The vertical arm 18 of the movable gripping-jaw is provided with two inwardly-projecting tappet-pins 20 20, (extending from the side of the arm 18 next the plate 10,) which are located, respectively, above and below the cam-bar *S*. The cam-bar has an inclined cam-face *u* on its upper surface and an inclined cam-face *v* on its lower surface. When the cam-bar is drawn out—that is, when it is moved radially away from the axis of the machine—its upper cam-face *u* encounters the upper tappet-pin 20 and pushes said pin before it, thus swinging the arm 18 outward and so releasing the splicing-thread. When the cam-bar is moved inward, however, its lower cam-face *v* encounters the lower tappet-pin 20, thus pushing the pin inward and consequently forcibly forcing the arm 18 of the gripping-jaw against the plate *F*, and so insuring a firm grip upon the splicing-thread.

It will be noted that when the cam-bar occupies either its outermost or innermost position the movable gripping-jaw is locked and cannot be swung on its pivot, this locking being due to the fact that the thickness of those portions of the cam-bar which lie on either side of the two cams *u v* is equal to the distance between the two pins 20 20, as indicated in Fig. 6. Consequently the movable gripping-jaw can only be moved when the cam-bar moves longitudinally. It will further be noted that before one pin (say the upper pin) is encountered by its cam *u* the other cam *v* will have passed beyond the other (lower) pin, so that the movable gripping-jaw is free to swing when the cam-bar occupies an intermediate position.

The cam-bar *S* carries on its outer end a downwardly-projecting tappet-pin *T*, into the path of which the cam-plate *R* is brought when the lever *Q* is lifted. (See Fig. 1.) When the cam-bar *S* and its tappet-pin *T* occupy their innermost position, the portion of the cam-plate *R* adjacent to the forward edge of the outer cam-face of the cam-plate *R* is in the path of the tappet-pin. (See Fig. 2.) That is, when the parts are in this position the forward edge of the outer cam-face of the cam-plate is nearer the axis of the machine than the tappet-pin. When therefore in its rotation the tappet-pin encounters the cam-plate, it travels on the outer cam-surface thereof, and in this manner the cam-bar *S* is drawn out, thus swinging outwardly the movable gripping-jaw of the gripper and leaving the splicing-thread free to be fed to the needles by the frictional contact therewith of the main thread. The movable jaw of the gripper then remains in its outward position for an interval depending upon the desired width of the patch, and while it is so swung outwardly the knitting with the splicing-thread continues. The movable jaw of the gripper is caused to swing inwardly and grip the thread (and so limit the width of the patch) by a stationary inclined cam-plate *U*, fixed at the desired position on the head-plate with its cam-face in the plane and path of the tappet-pin *T*. The coacting face of this cam faces the axis of the machine, so that when the tappet-pin is engaged thereby it forces the tappet-pin radially inward, thus moving in the cam-bar *S*, and so swinging the gripper inwardly, causing the latter to grip the thread, so that it is broken by the onward movement of the dial-plate *E*. The gripping-edge of the movable jaw of the gripper is in close proximity to the leading-in guide-eye in the guide-plate, so that the broken end of the splicing-thread is always left in the guide-eye, where it is subject to the frictional contact of the main thread the moment the gripper is raised. As long as the lever *Q* remains in its elevated position with the cam-plate *R* in the path of the gripper-controlling tappet-pin *T*, the movable jaw of the gripper will be raised and lowered at each round of stitches. When, how-

ever, through the instrumentality of the pattern-chain the inner rod M is lifted and the lever P is swung so that its projecting tongue q no longer upholds the lever Q, the cam-plate 5 R is lowered below the path of the tappet-pin and no longer co-operates therewith, so that the movable jaw of the gripper constantly occupies its normal lower position, gripping the splicing-thread and rendering it inoperative.

There only remains now to be described the construction of the present improved thread-slackener for slackening the splicing-thread and relieving it of all tension at the moment 15 when the movable gripping-jaw is swung outward, in order that the splicing-thread may with certainty and uniformity be fed in by the frictional contact therewith of the main thread. This is accomplished by means of a 20 slackening-lever 21, which is pivoted at 22 to a vertical post 23, carried by the bracket-arm G on the opposite side of the spindle a from the vertical plate 10. The long end of this 25 slackening-lever 21 is formed with a horizontally-extending thread-eye 24, and when the lever is in its normal position this thread-eye is located between the splicing-thread guides 11 and 12 in the same horizontal plane therewith, so that the splicing-thread in passing 30 from guide 11 to guide 12 passes through the thread-eye 24. The normal position of the eye end of the lever 21 is its elevated position, and it is maintained in this elevated position and normally resumes it when depressed by reason of the short tail end 35 of the lever being the heavier end. This slackening-lever rotates with the other rotary parts of the knitting-machine, and it is operated so as to depress its eyed end by means of 40 an inclined cam-plate Z, (see Fig. 4,) fixed to the head-plate A, the upper inclined cam-face c' of which is encountered by the tail end 25 of the slackening-lever during the rotary movement thereof. The tail end of the 45 slackening-lever travels up this inclined cam-face, thus lowering the eyed end of the lever. When the eyed end of the lever descends, it drags down the splicing-thread from the guide 11, consequently drawing down from the bobbin 50 a length of thread proportional to its extent of movement. When the tail end of the slackening-lever passes clear of the cam-plate Z, its weight causes it to descend, and so elevates the eyed end of the lever. This leaves 55 slack all of the additional thread drawn down by the lever, which is left in a loose loop. Consequently when the movable gripping-jaw releases the splicing-thread it is free of all tension and is fed in to the needles with 60 certainty and uniformity by the frictional contact therewith of the main thread.

The time of the slackening action of the slackening-lever 21 is determined by the position of the cam-plate Z. The slackening-lever should operate after the gripper has gripped the splicing-thread and broken it off,

and its operation should be completed before the gripper releases the thread. The relative positions shown in the drawings are correct, the respective positions of the several parts 70 being therein properly illustrated.

As compared with the mechanism set forth in the above-named application, the present improvements are seen to consist in the construction of the gripper, the construction of 75 the slackening-lever, and the location and arrangement of the guide-eyes for the splicing and main threads. The movable jaw of the gripper is simply a swinging lever co-operating with the usual thread-guide plate of 80 the knitting-machine as the stationary jaw. No special construction of the thread-guide plate is necessary. The relative positions of the gripper-jaws enable the splicing-thread to pass at all times behind the movable gripping-jaw, so that there is no opportunity for it to slip from beneath the jaw.

The guide-eye 16 for the main thread, through which the latter passes before entering the feeding-in eye c, is located in front of 90 the eye c so that the main thread extends between the two eyes clear of the movable gripping-jaw. Consequently the movement of the gripping-jaw does not affect the main thread, and there is no opportunity of the latter being caught beneath the movable gripping-jaw. To prevent the main thread from getting too 95 far above the thread-eye c, a laterally-projecting pin 26 is carried by the movable gripping-jaw above the main thread.

The last guide-eye 15, through which the splicing-thread passes before reaching the feeding-in eye c, is located with special reference to the movable gripping-jaw, so that the splicing-thread always passes behind the said 100 movable jaw. The other two guides 11 12 are located with special reference to the eye in the slackening-lever, so that a slack is formed by the rise and fall of the slackening-lever. It will be noted that when the eyed end of the slackening-lever descends the friction of the thread upon the guide 12 is greatly increased while that on the guide 11 is diminished, so that the pull on the thread comes almost exclusively upon that portion of the splicing-thread 110 which extends between guide 11 and the eye 24 in the slackening-lever.

The slackening-lever itself is a simple pivoted lever eyed at one end, weighted at the other end, and moving in a vertical plane. 115 The eyed end in its movement travels in a vertical plane to and from the lower guide-eye 15. This slackening-lever is carried with the rotary parts of the knitting-machine rotating with the dial-cam plate and the leading-in thread-guide plate F. The eyed end of the slackening-lever in giving down the splicing-thread moves toward the thread-guide plate, so that slack thread is left between its eye and the thread-guide plate when the eyed end 125 of the lever again rises.

The present improvements can be readily

applied to ordinary circular-knitting machines now in use, since no alteration of the usual parts is necessary.

We claim as our invention—

5 1. The rotating thread-guide plate of a circular-knitting machine having a leading-in thread-eye through which both the main thread and the splicing-thread pass, in combination with two thread-guides between which 10 the splicing-thread passes before reaching said leading-in thread-eye, said thread-guides rotating with said thread-guide plate and located thereabove in substantially the same horizontal plane, a swinging slackening-lever rotating with said guide-plate, said lever extending normally in a substantially horizontal plane and swinging in a vertical plane, and said lever having a thread-eye having normal position between said two thread-guides 15 and in substantially the same horizontal plane therewith, through which eye the splicing-thread passes in extending between said guides, the eyed end of said lever swinging down toward said guide-plate to slacken the 20 thread, and means for actuating said slackening-lever, substantially as set forth.

2. The rotating thread-guide plate of a circular-knitting machine having a leading-in thread-eye through which both the main 30 thread and the splicing-thread pass and the stationary cam-plate Z, in combination with two thread-guides between which the splicing-thread passes before reaching said leading-in thread-eye, said thread-guides rotating 35 with said thread-guide plate and located thereabove in substantially the same horizontal plane, and a swinging slackening-lever rotating with said guide-plate and extending normally in a substantially horizontal plane 40 and adapted to swing in a vertical plane, the rear end of said lever being weighted so that it maintains and automatically resumes (when displaced) its normal position, said rear end co-operating with said cam-plate Z, whereby 45 the movement of said lever is effected, and the other end of said lever having a thread-eye having normal position between said two thread-guides and in substantially the same horizontal plane therewith, through which 50 thread-eye the splicing-thread passes in extending between said guides, the eyed end of said lever swinging down toward said guide-plate to slacken the thread when actuated by said cam-plate Z, substantially as set forth.

55 3. The thread-guide plate of a knitting-machine having a leading-in eye through which both the main thread and the splicing-thread pass, and a guide-eye in front of said guide-plate and near said leading-in eye through 60 which the splicing-thread passes just before entering said leading-in eye, whereby said splicing-thread passes along the outer face of said guide-plate, in combination with a movable gripping-jaw which moves to and from 65 the outer face of said guide-plate between said guide-eye and said leading-in eye, where-

by it grips the splicing-thread against the outer face of said guide-plate, substantially as set forth.

4. A splicing-thread gripper composed of 70 the thread-guide plate of a knitting-machine having a leading-in thread-eye through which both the main thread and the splicing-thread pass, the outer face of said guide-plate constituting the fixed gripping-jaw, in combination with a movable gripping-jaw which moves to and from the outer face of said guide-plate, substantially as set forth.

75 5. A splicing-thread gripper composed of 80 the thread-guide plate of a knitting-machine having a leading-in thread-eye through which both the main thread and the splicing-thread pass, the outer face of said guide-plate constituting the fixed gripping-jaw, in combination with a movable gripping-jaw consisting 85 of a lever having a vertical arm extending along the outer face of said guide-plate and swinging to and from the same, substantially as set forth.

90 6. The thread-guide plate of a knitting-machine having a leading-in thread-eye through which both the main thread and the splicing-thread pass and a movable gripping-jaw which moves to and from said guide-plate at one side of said leading-in thread-eye and co- 95 operates with the outer face thereof to grip the splicing-thread, in combination with a splicing-thread guide-eye close to the outer face of said guide-plate and on the opposite side of said movable jaw from the leading-in 100 eye, whereby the splicing-thread passes between said movable jaw and the outer face of said guide-plate, and a main thread guide-eye located in front of the leading-in eye, whereby the main thread passes into said 105 leading-in eye without being encountered by said movable jaw, substantially as set forth.

110 7. A splicing-thread gripper composed of the thread-guide plate of a knitting-machine having a leading-in thread-eye through which both the main thread and the splicing-thread pass, the outer face of said guide-plate constituting the fixed gripping-jaw, and a movable gripping-jaw consisting of a lever having a vertical arm extending along the outer 115 face of said guide-plate and swinging to and from the same, said vertical arm having two projecting pins 20 20, in combination with a horizontally-movable cam-bar S for actuating said movable gripping-jaw, said cam-bar having cam-faces *u* *v*, which co-operate alternately with said pins 20 20, respectively, substantially as set forth.

120 In witness whereof we have hereunto signed our names in the presence of two subscribing 125 witnesses.
